[57] CLAIM

The ornamental design for an adjustable measuring spoon, as shown and described.

DESCRIPTION

FIG. 1 is a top, front, left side perspective view of the adjustable measuring spoon showing my new design;

FIG. 2 is a top, front, left side perspective view thereof in an alternate position;

FIG. 3 is a top plan view of FIG. 1;

FIG. 4 is a right side elevational view of FIG. 1;

FIG. 5 is a left side elevational view of FIG. 1;

FIG. 6 is a front elevational view of FIG. 1;

FIG. 7 is a rear elevational view of FIG. 1;

FIG. 8 is a bottom plan view of FIG. 1;

FIG. 9 is a top, front, left side perspective view, a modification, of the adjustable measuring spoon showing my new design;

FIG. 10 is a top, front, left side perspective view of FIG. 9;

FIG. 11 is a top plan view of FIG. 9;

FIG. 12 is a right side elevational view of FIG. 9;

FIG. 13 is a left side elevational view of FIG. 9;

FIG. 14 is a front elevational view of FIG. 9;

FIG. 15 is a rear elevational view of FIG. 9;

FIG. 16 is a bottom plan view of FIG. 9;
